US00D983471S

(12) **United States Design Patent** (10) **Patent No.:** **US D983,471 S**
Liao (45) **Date of Patent:** **** Apr. 11, 2023**

(54) **BLOWER**

(71) Applicant: **Shenghui Liao**, Shenzhen (CN)

(72) Inventor: **Shenghui Liao**, Shenzhen (CN)

(**) Term: **15 Years**

(21) Appl. No.: **29/865,034**

(22) Filed: **Jul. 2, 2022**

(51) **LOC (14) Cl.** **15-05**

(52) **U.S. Cl.**

USPC **D32/15**

(58) **Field of Classification Search**

USPC D15/12; D32/15-18

CPC F04D 29/545; F04D 29/522; A47L 5/14
